UNITED STATES PATENT OFFICE

WILLIAM N. THOMAS, OF NEW HAVEN, CONNECTICUT, ASSIGNOR TO SARGENT & COMPANY, OF NEW HAVEN, CONNECTICUT, A CORPORATION OF CONNECTICUT

DESIGN FOR A PLATE FOR CASKET HANDLES OR THE LIKE

Application filed January 22, 1930. Serial No. 34,231. Term of patent 14 years.

To all whom it may concern:

Be it known that I, WILLIAM N. THOMAS, a citizen of the United States, residing in New Haven, in the county of New Haven and State of Connecticut, have invented a new, original, and ornamental Design for a Plate for Casket Handles or the Like, of which the following is a specification, when taken in connection with the accompanying drawing, of which—

Figure 1 is a front elevation of a plate for casket handles or the like, embodying my new design; and

I claim:

The ornamental design for a plate for casket handles or the like substantially as shown.

WILLIAM N. THOMAS.
